Primary Examiner — Anhdao Doan(74) **Attorney, Agent, or Firm — Baird Holm LLP**(57) **CLAIM**

The ornamental design for a wearable MRI pelvic coil, as shown and described.

DESCRIPTION

FIG. 1 is a front perspective view of a wearable magnetic resonance imaging (MRI) pelvic coil.

FIG. 2 is a front view of the wearable MRI pelvic coil of FIG. 1.

FIG. 3 is a bottom view of the wearable MRI pelvic coil of FIG. 1.

FIG. 4 is a first side view of the wearable MRI pelvic coil of FIG. 1.

FIG. 5 is a second side view of the wearable MRI pelvic coil of FIG. 1.

FIG. 6 is a back view of the wearable MRI pelvic coil of FIG. 1.

FIG. 7 is a top view of the wearable MRI pelvic coil of FIG. 1.

FIG. 8 is a bottom view of an open position of the wearable MRI pelvic coil of FIG. 1 to show the outside of the wearable MRI pelvic coil; and,

FIG. 9 is a top view of the wearable MRI pelvic coil of FIG. 1 to show the inside of the wearable MRI pelvic coil.
